PROCESS FOR CONVERTING HYDROCARBON COMPOUNDS

Filed Jan. 3, 1927

UNITED STATES PATENT OFFICE.

MYRON W. COLONY, OF TEXAS CITY, TEXAS, ASSIGNOR TO PETROLEUM CONVERSION CORPORATION, OF NEW YORK, N. Y., A CORPORATION OF DELAWARE.

PROCESS FOR CONVERTING HYDROCARBON COMPOUNDS.

Application filed January 3, 1927. Serial No. 158,757.

My present invention relates to a process for converting or cracking hydrocarbon compounds into compounds of lower molecular weight and more particularly it seeks to utilize steam in a manner to improve the efficiency of the process and the quality of the product.

In accordance with the process disclosed in the United States Patent to Knox, No. 1,428,641, the oil is heated to the cracking temperature by contacting therewith hydrocarbon gases of sufficient temperature and heat units. In a subsequent pending application, Serial No. 587,191, Knox disclosed improved means for heating the gases constituting the heat carrier, such means being of the regenerative type. Experimental work has demonstrated that when hydrocarbon gases are used there is the tendency to deposit carbon in the checker-work, or other refractory bodies constituting the regenerative heater. This carbon deposit, while it permits the process to be carried on for periods of time, is nevertheless troublesome, since the stove must be periodically disconnected from the system and cleaned, as a carbon deposit of more than a certain amount cuts down the efficiency of the stove.

The reasons for using a hydrocarbon gas as a heat carrier, are set forth in the patent and application above referred to. Chief among these, is that in any cracking reaction there are produced large quantities of non-condensable gases, which are available for use in this way. Furthermore, it is considered that these gases of hydrocarbon origin may afford a more favorable atmosphere for the cracking reaction than do purely neutral gases which, if used, would not deposit carbon on the checker-work.

I have now discovered that a satisfactory solution of the above mentioned difficulty will be had by the use, along with the hydrocarbon gases, of considerable amounts of steam. In other words, I have found the presence of the steam in the blast stoves inhibits the deposition of carbon to a satisfactory degree without adversely affecting the action of the heated hydrocarbon gases in the conversion chamber. Moreover, when steam is used, it will be found that after the products of the system have traversed the condenser, the volume of gases uncondensed will of course be smaller, and this will facilitate the stripping therefrom of the light vapors, the pres-

ence of which is so desirable in motor fuels. With respect to the nature of the action of the steam in inhibiting the deposition of the carbon, I attribute same to its property of combining with the carbon at sufficiently elevated temperature to produce carbon oxides and hydrogen.

In case some carbon is formed the amount will be so slight as to permit of its ready combustion during the blasting period.

I have illustrated suitable apparatus for carrying out the invention in the accompanying drawing forming part of this specification. In this drawing the figure shows diagrammatically a layout of a plant in which my invention may be practised.

Referring thereto by characters of reference, 10 denotes a regenerative heating means which conveniently is of the type used in the blast furnace art and commonly designated a hot blast stove, stove 10 having an inlet 12 for steam and inlet 14 for oil or other fuel for heating the stove. Said stove, as is customary, contains refractory, inert checker-work preferably forming vertical flues as shown. Adjoining the stove 10 is a stack 16 connected thereto by means of a pipe 17. The fluids, heated in the stove are led therefrom through the pipe 18 and are admitted to a conversion chamber 20 which may be provided with checker-work 21 for the purpose of insuring mixing of the gas and oil.

Oil is also admitted to the chamber, preferably in vapor form, being generated in the still 23 of known type, and conveyed therefrom into said chamber through pipe 24. The oil is fed to the system preferably through a preheater 25 and pipe 26, leading therefrom to the still 23. The products of the reaction chamber leave the chamber through pipe 28, thence through preheater 25, where they give up a part of their heat to the incoming oil, after which they are passed to a condenser 29, it being understood that various intermediate apparatus may also be employed, whereby to fractionally condense the products and also to heat the incoming oil. As disclosed in the Knox application before mentioned, I find it desirable to pass a part of the vapors generated from the incoming oil in the preheater 25 back into the reaction chamber 20 employing pipe 25^a for this purpose.

The products which pass through the condenser 29 are thus separated into the con-

densible materials which may comprise water and the lighter liquid hydrocarbons collecting in the receiver 30, whereas the gases which are uncondensed pass through pipe 31 into the receiver 32 or are returned to the stoves, as desired. Normally they are conducted through a pipe 33 back into stove 10, being assisted thereto by means of a pump 34. Receiver 32 is cut in and out of the system by using valves 32^a, 32^b and 32^c. Preferably, I interpose a stripper or absorber 31^a of known type after the accumulator 30 whereby to remove the condensable vapors which are valuable in motor fuels and which otherwise would be fed to the hot blast stoves and lost.

It will be understood that the stove 10 is one of a battery not shown, and that in starting the process a stove 10 will be brought up to temperature in the usual way by burning therein a suitable fuel, such as fuel oil or combustible gas. After the stove has thus been brought up to temperature steam through pipe 12 and hydrocarbon gas through pipe 33 or other source will be admitted to the stove, and pass therethrough and thence into the conversion chamber 20. Simultaneously with this, oil vapor will be admitted to the chamber from still 23, by means of pipe 24. The temperature for cracking may be taken from 700° to 800° F., as a minimum and the temperature prevailing in the blast stove will in general run from 1500° to 1800° F. It will be understood that the temperature of the gases will be suitably regulated by commingling therewith a portion of the cold gas which is by-passed through pipe 35 into the pipe 18. Ordinarily this will be accomplished automatically by thermostatically controlled means.

After a stove has "run" until its temperature has dropped below the desired minimum, it is cut out of the system and "blasted" with a suitable fuel. As has been previously mentioned, in case a slight deposit of carbon is left in the stove, a sufficient excess of air is admitted in the blasting period to consume this, as well as the fuel added. In this way the stoves are connected and efficiently heated to the desired temperature, after which they are cut into the system in an obvious way.

It will be understood that in view of the intense heat to which the hydrocarbon gases are subjected in the hot blast stoves, such gases will undergo decomposition to a considerable degree, and their composition will approach a mixture of hydrogen and methane almost entirely. Accordingly in the claims, the expression hydrocarbon gases will be understood to include gases of this general composition.

What I claim is:

1. The process of treating hydrocarbon compounds to convert the same into others of lower molecular weight, which consists in sep-

arately vaporizing the hydrocarbons to be converted without substantial cracking thereof, passing said vapor into a substantially non-externally heated reaction chamber, heating up a mass of inert heat retaining material until said material is at the requisite temperature, passing a mixture of steam and hydrocarbon gases thereover, and thence into said reaction chamber wherein to contact with the said vaporized hydrocarbon, said mixture of steam and hydrocarbon gases having been heated by its passage over said inert material to such a temperature and being of such relative volume as to accomplish substantially the entire reaction of conversion and constituting substantially the sole source of heat therefor, controlling the temperature of the reacting compounds whereby the conversion of said hydrocarbon is brought about under substantially uniform temperature conditions, the products from said reaction chamber containing the vapors of the desired compounds of the process in addition to the steam and hydrocarbon gas, and subjecting the products from said chamber to conditions producing liquefaction of said compounds suitable as motor fuels.

2. In the process of treating petroleum oils to convert them into compounds suitable as motor fuels, the steps which consist in maintaining a quantity of petroleum compounds undergoing treatment in a closed reaction chamber, heating up a mass of inert, refractory, heat absorbing material until said material is above the temperature required for the conversion reaction, passing a carrier gas including steam thereover, and thence into said reaction chamber, controlling the temperature of the said reacting compounds whereby the conversion of said petroleum compounds is brought about under substantially uniform temperature conditions, the products from said chamber containing the vapors of the desired compounds of the process in addition to the carrier gas, and subjecting the products from said chamber to conditions producing liquefaction of said compounds suitable as motor fuels.

3. The process of treating hydrocarbon compounds to convert them into compounds suitable as motor fuels, the steps which consist in heating up a mass of inert, heat retaining material until said material is above the conversion temperature, passing a mixture of hydrogen containing gas and steam thereover, and thence into a reaction chamber, separately vaporizing the hydrocarbon to be converted without substantial cracking thereof, introducing the vapor produced by the evaporating step mentioned into contact with the thus heated mixture of hydrogen containing gas and steam in said chamber, controlling the temperature of the reacting compounds whereby the conversion of said hydrocarbons is brought about under sub-

stantially uniform temperature conditions, the products from said chamber containing the vapors of the desired compounds of the process in addition to the carrier gas, and subjecting the products from said chamber to conditions producing liquefaction of said compounds suitable as motor fuels.

4. In the process of treating hydrocarbon oils to convert them into compounds suitable as motor fuels, the steps which consist in heating up a mass of inert, refractory, heat absorbing material until said material is above the temperature required for the conversion reaction, passing a heat-carrier gas including steam thereover, adding a varying quantity of relatively cold gas to said heated gas as said mass cools down, whereby the produced mixture is maintained at a substantially uniform temperature above the conversion

temperature, then introducing said heated mixture into a reaction chamber, separately vaporizing the hydrocarbon to be converted without substantial cracking thereof, introducing the produced vapor into contact with said heated mixture in said reaction chamber, whereby the conversion of said hydrocarbon is brought about under substantially uniform temperature conditions, the products from said chamber containing the vapors of the desired compounds of the process in addition to the carrier gas, and subjecting the products from said chamber to conditions producing liquefaction of said compounds suitable as motor fuels.

In testimony whereof I have affixed my signature to this specification.

MYRON W. COLONY.
